UNITED STATES PATENT OFFICE.

CHARLES F. BARRETT, OF NEW YORK, N. Y.

VALVE.

SPECIFICATION forming part of Letters Patent No. 285,871, dated October 2, 1883.

Application filed December 14, 1882. (No model.)

To all whom it may concern:

Be it known that I, CHARLES F. BARRETT, a citizen of the United States, residing in the city of New York, county of New York, and State of New York, have invented certain new and useful Improvements in Valves, fully described and represented in the following specification and the accompanying drawings, forming a part of the same.

This invention relates to that class of valves which are most commonly used in water, steam, gas, and other pipes to regulate and control the flow and pressure of the liquid, steam, or other fluid. These valves commonly consist of a disk-like head attached to a screw-threaded stem extending through the casing in which the valve is located, and provided with a handle by which it can be operated to move the valve to and from its seat, the seat being provided with an opening through which the liquid, steam, or other fluid passes when the valve is raised. It is found in practice that the rotary movement thus given to the valve in opening and closing has a constant tendency to wear the valve and seat away, so that valves of this construction which are frequently opened and closed soon become so worn as to require renewal.

In the constructions heretofore adopted the valve-seat has been made integral with the casing, so that the renewal of the seat entailed the expense of a new casing and the trouble of removing the same from the supply-pipe.

It is the object of the present invention, among other things, to lessen the expense and trouble attending the renewal of worn-out parts; and to this end one feature of the invention consists in making both the valve and seat removable, so that either or both can be renewed, when worn, without changing the remainder of the apparatus.

Another object of the invention is to increase the durability of the valve and seat; and to this end another feature of the invention consists in making both the valve and seat reversible, so that when one of their surfaces is so worn as to be worthless they can be reversed, thereby presenting entirely new bearing-surfaces.

In the accompanying drawings, Figure 1 is a vertical section of a valve apparatus em-

bodying the invention in one of its forms. Fig. 2 is an elevation, upon an enlarged scale, of the valve detached from its stem. Fig. 3 is a like view of the valve-seat. Fig. 4 is a plan view of Fig. 2. Fig. 5 is a like view of Fig. 3; and Fig. 6 is a sectional detail, showing a different way of attaching the valve to its stem.

As shown in the drawings, the apparatus consists of the usual casing, 1, provided with a transverse partition, 2, which supports the valve-seat 3, said casing being provided with an opening of sufficient size to permit the passage of the valve and seat, which opening is closed by a screw-plug, 5, in which works a screw-rod, 6, to the end of which is secured the valve 7. The casing 1 is provided with the usual threaded portions, 8, to receive the ends of the supply-pipe, and the plug 5 is provided with the usual stuffing-box, 9, to make a tight joint around the rod 6.

The valve-seat 3, instead of being formed in or made integral with the partition 2, is made separate therefrom, it being provided upon its outer periphery with a flange, 10, which rests upon the edge of the opening in the partition, and is secured thereto by means of screws passing through holes 11. Instead of being provided with a flange 10, as shown, the valve-seat may, if preferred, be provided with screw-threads, which engage with corresponding threads upon the edge of the opening in the partition, so that the seat can be screwed into and out of position. The inner periphery of the valve-seat is provided with a narrow flange, 12, in which are cut a series of nicks, 13, which can be engaged by a suitable tool for removing and inserting the seat.

The valve-rod 6 is provided at its inner end with a head, 14, above which rests a collar, 15, the under side of which is provided with an annular screw-threaded projection, 16, which is adapted to engage with the interior threaded portions, 17, of the valve and secure it to the rod, as shown in Fig. 1.

By reference to the drawings it will be observed that the opposite edges, 18 19, of the valve-seat are both so shaped as to afford bearing-surfaces for the valve, and that the opposite edges, 20 21, of the valve are so shaped as to fit these bearing-surfaces. From this con-

struction and arrangement it will be seen that when one edge of the valve, as 20, and one of the bearing-surfaces of the seat, as 18, have become so worn as to be worthless a practical renewal of the worn-out parts can be effected by simply removing the plug 5 and reversing the valve and seat so as to bring the edges 19 21 into co-operative relation. It will also be seen that when both edges of the valve and seat have become so worn as to be worthless they can be readily replaced by new parts without disturbing or sacrificing the remainder of the apparatus, thus saving much annoyance and expense.

15 A part of the advantages of the invention as thus far described may, as will readily be seen, be secured by simply making the valve and seat removable in the manner shown, without making them reversible.

20 The advantages of a removable and reversible valve and seat may be secured when the meeting edges of the valve and seat are of any ordinary form; but I have found that the apparatus is much more reliable and satisfactory when the meeting surfaces are of the form shown—that is to say, when one surface is grooved and the other tongued. The order of the grooving and tonguing may of course be varied from what is shown. Both edges of the seat may be grooved, as 19, or both may be tongued, as 18, the edges of the valve being the reverse.

25 30 The valve, instead of being secured to its rod

in the manner shown in Fig. 1, may be secured thereto in any other approved manner—as, for example, as shown in Fig. 6, in which case the 35 rod 6 is provided with a threaded extension, 22, which passes through an opening in the valve, and is provided at its end with a nut, 23.

What I claim is—

1. The combination, with the casing 1 and rod 6, of the removable valve and removable seat, substantially as and for the purpose set forth.

2. The combination, with the casing 1 and rod 6, of a reversible valve, as 7, and a reversible valve-seat, as 3, substantially as set forth.

3. The combination, with the casing 1 and rod 6, of a reversible valve, as 7, and a reversible valve-seat, as 3, the opposite edges of both valve and seat being provided with co-operating grooves and tongues, substantially as set forth.

4. A removable valve-seat, as 3, provided upon its inner periphery with notches or projections to receive a suitable tool for removing the same, substantially as described.

In testimony whereof I have hereunto set my hand in the presence of two subscribing witnesses.

CHARLES F. BARRETT.
